UNITED STATES PATENT OFFICE.

ALMERON F. WHEATON, OF MENLO, WASHINGTON.

SNATCH-BLOCK.

No. 821,148.

Specification of Letters Patent.

Patented May 22, 1906.

Application filed August 14, 1905. Serial No. 274,149.

To all whom it may concern:

Be it known that I, ALMERON F. WHEATON, a citizen of the United States, residing at Menlo, in the county of Pacific and State of Washington, have invented certain new and useful Improvements in Snatch-Blocks; and I do declare the following to be a full, clear, and exact description of the invention, such as will enable others skilled in the art to 15 which it appertains to make and use the same.

This invention relates to improvements in snatch-blocks.

The object of the invention is to provide a 15 snatch-block or pulley having means whereby the same may be quickly and easily opened for engagement with a rope or cable.

Another object is to provide means whereby the pulley may be closed and automatically 20 locked and securely held in said locked position.

A further object is to provide a snatch-block of this character which will be simple, strong and durable in construction, efficient 25 and reliable in operation, means being provided whereby the wear on the pulley-wheel will be reduced to a minimum.

With the above and other objects in view the invention consists of certain novel features of construction, combination, and arrangement of parts, as will be hereinafter described and claimed.

In the accompanying drawings, Figure 1 is a side view of one side of the block. Fig. 2 is 35 a similar view of the opposite side. Fig. 3 is an edge view thereof, and Fig. 4 is a central vertical sectional view on the line 4-4 in Fig. 1.

Referring more particularly to the drawings, 1 denotes the frame of the block, said 40 frame consisting of tapering parallel side plates 2 and 3, connected together at their lower ends by an integral cross-bar or plate 4. The side plates 2 and 3 are preferably formed with a beaded or reinforced edge 5, 45 and the plate 2 is integrally formed or otherwise secured to a reinforcing-plate 6. The side plate 3 is provided with a reinforcing-plate 7.

Arranged in the side and reinforcing plates 50 is a central transversely-disposed pivot bolt or pin 8, which is preferably formed of comparatively soft metal and is incased in a band or sleeve 10 of hard metal, the length of the band or sleeve 10 being such that the ends of 55 the same will engage the inner walls of the side plates 2 and 3, thereby holding said

plates properly spaced apart to permit the grooved pulley-wheel 9 to freely revolve on said band or sleeve, said plates, together with the pivot-bolt 8, firmly bracing said side 60 plates and the frame of the pulley, as well as preventing the wearing of the bolt or pin 8.

The reinforcing-plate 6 on the side plate is provided with laterally-projecting parallel apertured lugs 12, between which is pivotally 65 mounted a right-angular supporting-bail 13. On the free end of the bail 13 is formed a reduced lug 14, on the inner side of which is formed an inwardly-projecting extension 15, the inner face of which is beveled or inclined, 70 as shown at 16, and is adapted to engage a similarly beveled or inclined surface formed on the outer end of the reinforcing-plate 7 of the side plate 3, whereby when said extension of the lug 14 is in engagement with the 75 beveled surface of the plate 7 the upper ends of the side plates 2 and 3 will be securely braced and prevented from spreading.

On the reinforcing-plate 7 of the side plate 3 is formed a laterally-projecting apertured 80 lug or ear 17, on which is pivotally mounted a bail-shaped latch 18, said latch being adapted to be swung into engagement with the outer edge of the lug 14, thereby locking the same into engagement with the side plate 3, 85 as hereinbefore described. The pivot-pin 19 of the latch 18 is provided on one end with an offset or cam lug 20, which is adapted to be engaged by a flat spring 21, secured to the side 3 of the block. The tension of the spring 90 21 is exerted upon the cam-lug 20 to normally hold the latch 18 in position to be engaged by the lug 14, with which said latch will be automatically engaged when the bail 13 is swung to a closed position over the end of the block, 95 thereby automatically securing said supporting-bail into closed position. In the upper right-angularly-bent portion of the bail 13 is swiveled an eyebolt 22, with which is connected a link 23, and to said link is connected 100 a supporting-hook 24, by which the block is connected to a suitable anchorage.

A pulley-block constructed as herein shown and described may be quickly engaged with and disengaged from a rope or pulley at 105 any suitable point on the same.

From the foregoing description, taken in connection with the accompanying drawings, the construction and operation of the invention will be readily understood without requiring a more extended explanation.

Various changes in the form, proportion,

and the minor details of construction may be resorted to without departing from the principle or sacrificing any of the advantages of this invention.

5 Having thus described my invention, what I claim as new, and desire to secure by Letters Patent, is—

10 1. A pulley-block of the class described, consisting of parallel side plates connected together at their lower ends, a grooved pulley journaled in said plates, reinforcing-plates arranged on said side plates, apertured parallel bearing-lugs formed on one of the latter, a right-angularly-formed supporting-bail 15 pivotally mounted in said parallel lugs, a lug formed on the end of said bail, said lug having an inwardly-projecting beveled extension adapted to engage a beveled surface on the reinforcing-plate of the opposite side plate, 20 an apertured lug formed on said latter reinforcing-plate, a bail-shaped latch pivotally mounted on said lug and adapted to be swung into engagement with the lug on said supporting-bail to hold the same closed, and 25 means to hold said latch against casual disengagement from said lug, substantially as described.

2. A pulley-block of the class described, consisting of parallel side plates connected to-

gether at their lower ends, a grooved pulley 30 journaled in said plates, reinforcing-plates arranged on said side plates, apertured parallel bearing-lugs formed on one of said side plates, a right-angularly-formed supporting-bail pivotally mounted in said parallel lugs, a 35 lug formed on the end of said bail, said lug having an inwardly-projecting beveled extension adapted to engage a beveled surface on the reinforcing-plate of the opposite side plate, an apertured lug formed on said latter 40 reinforcing-plate, a pivot-pin journaled in said apertured lug, a bail-shaped latch fixed on said pin and adapted to be swung into engagement with the lug on said supporting-bail, an offset lug formed on one end of said 45 pin and a spring adapted to be engaged by said offset, whereby said latch will be held against casual disengagement from the lug on said supporting-bail, substantially as described. 50

In testimony whereof I have hereunto set my hand in presence of two subscribing witnesses.

ALMERON F. WHEATON.
